(57) **CLAIM**

The ornamental design of the modular floor stand, as shown and described.

DESCRIPTION

FIG. 1 is a perspective view of the modular floor stand showing a first embodiment of my new design;

FIG. 2 is a front view thereof;

FIG. 3 is a back view thereof;

FIG. 4 is one side view thereof;

FIG. 5 is the other side view thereof;

FIG. 6 is a top view thereof;

FIG. 7 is a bottom view thereof;

FIG. 8 is perspective view of a second embodiment of my invention;

FIG. 9 is a front view FIG. 8;

FIG. 10 is a back view FIG. 8;

FIG. 11 is one side view FIG. 8;

FIG. 12 is the other side view FIG. 8;

FIG. 13 is a top view FIG. 8; and,

FIG. 14 is a bottom view FIG. 8.
